UNITED STATES PATENT OFFICE.

LEWIS F. BETTS, OF NEW YORK, N. Y., ASSIGNOR TO THE R. E. DIETZ COMPANY, OF SAME PLACE, AND THE STEAM GAUGE AND LANTERN COMPANY, OF SYRACUSE, NEW YORK.

TUBULAR LANTERN.

SPECIFICATION forming part of Letters Patent No. 498,420, dated May 30, 1893.

Application filed August 10, 1891. Serial No. 402,212. (No model.)

To all whom it may concern:

Be it known that I, LEWIS F. BETTS, a citizen of the United States, residing at New York, in the county and State of New York, have 5 invented a new and useful Improvement in Tubular Lanterns, of which the following is a specification.

One part of this invention relates to the tubular lantern frame and has the object to 10 increase the strength and rigidity of the upper portion thereof; another part of my invention relates to the catch whereby the loose burner cone is fastened upon the air chamber and has the object to increase the elasticity 15 of the catch and to render its manipulation more convenient.

In the accompanying drawings: Figure 1 is 20 an oblique side elevation of a tubular lantern provided with my improvements. Fig. 2 is a fragmentary horizontal section through the upper part of the lantern in line $x-x$ Fig. 1 looking upward, on an enlarged scale. Fig. 3 is an oblique elevation of the upper part of 25 a tubular lantern showing a modified construction of the strengthening device. Fig. 4 is a horizontal section in line $y-y$ Fig. 3. Fig. 5 is a side elevation of the upper part of the lantern showing another modification of 30 the strengthening device. Fig. 6 is a sectional 35 elevation of the lower part of the lantern at right angles to Fig. 1. Fig. 7 is a horizontal section through the lower part of the lantern in line $z-z$ Fig. 1. Fig. 8 is a perspective view of the catch by which the burner cone is locked down upon the air chamber.

Like letters of reference refer to like parts in the several figures.

A represents the oil pot, a the air chamber mounted thereon, b the lower horizontal 40 branches of the air tubes secured to the top of the oil pot and opening into the air chamber, B the upright portions of the air tubes, c the horizontal top branches thereof and C the central depending tube arranged between the 45 top branches and secured thereto. All of these parts may be of any ordinary or suitable construction.

The upper part of the lantern is inferior in strength and rigidity to the lower part and is 50 particularly liable to become bent or broken,

where the upper horizontal branches of the tubes join the depending central tube. In order to avoid this I strengthen the upper part by a strengthening piece D which connects the central tube with the top branches 55 and side portions of the air tubes. As represented in Figs. 1 and 2 the strengthening piece D consists of a wire or rod which is arranged against the under side of the top branches of the air tubes and provided with downwardly 60 projecting or depending end portions d which are arranged against the inner sides of the upright portions of the air tubes. The wire or rod D is provided with a central bend or bow e which rests against one side of the central depending tube. This wire or rod is soldered to the upper portion of the tubular frame and forms a firm connection between the upper horizontal branches and the central tube and between the upright side portions 65 and the horizontal top branches. 70

In the construction represented in Figs. 3 and 4 the wire or rod D is constructed without the central bend and extends through the central depending tube instead of around it. 75

In the construction represented in Fig. 5 the strengthening device is formed by a flat bar which is secured against one side of the lantern frame and extends from the top part of one upright side portion along the side of 80 the adjacent horizontal branch, then around one side of the central tube, and along the side of the other horizontal branch to the top part of the other upright side portion of the tube. 85

E represents the burner cone which is loosely fitted with its skirt upon the upper edge of the air chamber a . F represents the pivoted wire catch whereby the cone is locked down upon the air chamber. This catch is composed of two vertical legs f arranged on diametrically opposite sides of the cone, a semi-circular bow g connecting the upper ends of the legs and adapted to bear upon the shoulder of the cone, and a thumb-piece h formed 90 on the bow, as described and shown in Letters Patent No. 397,625, granted to me February 12, 1889. In the construction represented in this patent the legs of the catch are pivoted to the upper sides of the lower hori- 95 100

zontal branches of the side tubes. This ren-
ders the legs so short that the catch is not
sufficiently elastic to lock easily over the
shoulder of the cone. In order to overcome
5 this difficulty I extend the legs down to the
lower portion of the air chamber and provide
them with inwardly projecting pivots *i* which
are sprung into openings formed in the air
chamber. This construction increases the
10 length of the legs and provides the requisite
elasticity in the catch, thereby enabling the
catch to be conveniently manipulated.

I claim as my invention--

1. The combination with the upright side
15 portions of the air tubes, their upper branches
and the central depending tube, all rigidly
secured together, of a strengthening bar rig-
idly secured to the under sides of the branches
and to the central tube and provided with de-
20 pending end pieces which are secured to the
side portions of the tubes, substantially as set
forth.
2. The combination with the upper branches

of the air tubes and the central depending
tube rigidly secured together, of a strength-
ening bar rigidly secured to the side portions
and provided with a bend which extends
around one side of the central tube and is
rigidly secured thereto, substantially as set
forth.

3. The combination with the air chamber
and the burner cone seated thereon, of a catch
provided with a bow bearing upon the cone
and with legs extending downwardly from the
bow on opposite sides of the air chamber and
35 provided at their lower ends with inwardly
projecting pivots which turn in openings
formed in the side walls of the air chamber,
substantially as set forth.

Witness my hand this 16th day of July, 40
1891.

LEWIS F. BETTS.
